JEWELRY CLIP

Michael Chernow, New York, N. Y.

Application October 16, 1946, Serial No. 703,548

5 Claims. (Cl. 63—14)

1

The present invention relates to jewelry clips and more particularly to earrings of the hinged clip type.

The invention is an improvement upon that of my prior Patent No. 2,351,925 of June 20, 1944, which also relates to earrings of the hinged clip type.

Among the objects of this invention are to provide a jewelry clip and more particularly an earring clip which is simple to construct and has a minimum number of inexpensive parts and which is devoid of springs, ratchet or screw locking adjustments that are subject to wear, jamming or derangement in use, which frequently result on the one hand in discomfort to the wearer due to pinching the ear lobe, or on the other in looseness and loss of the clip, the clip of the present invention affording simple means for tightening the hinge portion in the event of looseness thereof and inherently affording a secure hold without pinching the ear lobe, regardless of its thinness or thickness.

In the accompanying drawings in which are shown one of various possible embodiments of the several features of the invention,

Fig. 1 is a side elevation of the earring clip in use.

Fig. 2 is a rear view of the earring with the clip arm in clamped position.

Fig. 3 is a rear view of the earring with the clip arm in open position, and

Fig. 4 is a fragmentary sectional view taken along line 4—4 of Fig. 1.

Referring now to the drawings, there is illustratively shown an earring clip which comprises the ornamental face member or plate 10 to the rear of which is soldered, brazed, welded or otherwise attached the base of a U-shaped bracket 11, the outer parts of which constitute upstanding jaws 12. Between the jaws 12 of the bracket is hinged a clip arm 14, desirably a stamped metal clip arm or one blanked out of sheet metal stock of uniform thickness. This arm desirably includes an eye 15 interposed between the jaws of the bracket. A rivet 16, placed transversely through the bracket jaws and the interposed eye 15, securely clamps the latter in place between said jaws. Desirably the eye has a bore slightly larger than the shank of the rivet, the latter being frictionally held as an axle in the two bracket jaws 12.

In the earring embodiment particularly, the width of the clip arm 14 extends generally parallel to the length of the rivet and the plane of the eye is at right angles to said arm, the metal

2

of the arm being twisted for that purpose at 17 at a point near, but beyond the jaws 12 of the bracket, affording a shank portion 18 between the eye 15 and the twist 17. The clip arm preferably flares outward toward its free end, which presents a generally convex holding cup conformation 19 of substantial width in the neighborhood of $\frac{1}{8}$ inch. The convex holding cup end 19 desirably has transverse ribs 20 across the face thereof extending parallel to the rivet to more securely hold the earring clip on an ear when the ear lobe is squeezed between holding cup 19 and the rear of plate 10.

The construction thus far described is not necessarily claimed herein as it is the subject of my prior patent above identified.

According to the present invention, each of the jaws 12 of said bracket has an asymmetrical resilient tongue portion 13 unitary therewith. 20 The tongues 13 are transversely aligned and substantially in the planes and at right angles to the lengths of the respective bracket arms, the lengths of said tongues extending in the general direction of the ear lobe engaging area of the 25 plate 10. The ends of said tongue portions turn inwardly but do not touch.

In the assembled unit, when the clip arm is in the opened position, as shown in Fig. 3, it does not extend between the ends of the tongues 13. 30 When the clip arm is pivoted to the position of use, as shown in Figs. 1 and 2, the shank portion 18 is forced between the converging ends of said tongues and wedged therebetween.

The shank portion 18 of the clip arm is slightly longer than the tongues 13, so that when the clip arm is pivoted from the open to the closed position of use, the converging tongues will only engage the shank of the clip arm and not the twisted portion thereof. Unnecessary spreading of the tongues is thus avoided and smooth pivoting of the clip arm from open to closed position occurs with firm frictional hold of the clip arm by the tongues when the clip arm is in use, thereby keeping the arm from easy displacement out of any position in which it is set when closed. When the clip arm is open, no pressure is exerted by the tongues against the shank of the clip arm, thereby releasing the strain on the tongues so that they will maintain their resiliency for a long time when the earring clip is not in use.

The inner sides 13' of the tongues are rounded and the tongues are so placed on the periphery of jaw 12 that the lower edge 21 of the lobe 55 of the ear may comfortably fit between the rear

of plate 10 and the rounded portion 13' of tongue 13 without pinching or cutting.

As the width of the shank portion 18 of the clip arm 14 is greater than the width of the clamping ends of the tongue, the clip arm, when in the closed position, will be firmly held by said tongues regardless of the thickness of the ear lobe.

The clip arm 14 is of such length, as shown in Fig. 1, that when the clip is applied to the ear with the bracket 11 against the lower edge 21 of the lobe, the convex gripping cup 19 of the arm will rest in the concavity 22 of said lobe, the human ear lobe presenting considerably more flesh about its entire rim 23 than it does in its mid-portion 22.

Thus in use the clip can be instantly applied to the ear, the gripping cup 19 becoming registered with the concavity 22 in the ear lobe and the tongue portions 13 maintaining the clip in any position of pivoted adjustment on an ear. The relatively large surface of the holding cup on the clip arm and the transverse ribs 28 thereof enhance the frictional hold and also prevent angular displacement of the earring from its initial set position.

In my prior patent heretofore referred to, the eye of the clip arm is split and the ends thereof are displaced laterally in the manner of a lock washer. In the assembled unit, the pressure exerted by the rivet brings the ends of the eye in line, so that in its tendency to spread out, it exerts a frictional hold against the jaws of the bracket. It has been found that after considerable use, the displaced ends of the eye tend to remain aligned, thereby loosening the hinge portion of the earring and allowing displacement of the clip arm. In order to tighten the hinge, it had to be disassembled, the ends of the split eye had to be displaced and the hinge reassembled. This operation required considerable effort and necessitated return of the earring to the factory.

According to the present invention, if the hinge does loosen due to a spreading of the lip portion of the jaws, it is merely necessary to move the clip arm to the open position out of engagement by the tongues, and to squeeze the ends of the tongue portions 13 of the jaws together, a relatively simple operation that can be performed by the user with an ordinary pair of pliers.

As many changes could be made in the above construction and many apparently widely different embodiments of this invention could be made without departing from the scope of the claims, it is intended that all matter contained in the above description or shown in the accompanying drawings shall be interpreted as illustrative and not in a limiting sense.

Having thus described my invention, what I claim as new and desire to secure by Letters Patent of the United States is:

1. A jewelry clip comprising a face plate, a bracket rigidly affixed to the back thereof and having a pair of jaws, each of said jaws having a tongue portion unitary therewith, said tongue portions being in registry and converging at the ends thereof, a metal clip arm having an eye unitary therewith at right angles to the general plane thereof and interposed between said jaws, a rivet transversely through said jaws and said interposed eye to clamp said eye in place between said jaws, said clip arm having a shank portion between and frictionally engaged by said tongues when the clip is in use.

2. A jewelry clip comprising a face member, a bracket having a base rigidly affixed to the back thereof and having a pair of jaws, each of said jaws having a resilient tongue portion unitary therewith, said tongue portions being in registry and converging at the ends thereof, a metal clip arm having an eye unitary therewith at right angles to the general plane thereof and interposed between said jaws, means frictionally to clamp said eye between said jaws, said means comprising a rivet transversely through said jaws and said interposed eye, said clip arm having a shank portion between and engaged by said tongues when the clip arm is closed, said rivet being frictionally held as an axle in said bracket and said eye having clearance with respect to said rivet.

3. An article of clip jewelry comprising a face member, a U-shaped bracket secured to the rear thereof and having a pair of jaws extending therefrom, each of said jaws having a tongue portion unitary therewith at right angles to the length of said bracket, said tongue portions being aligned and converging toward each other at the ends thereof, a clip arm having an eye unitary therewith hinged at one end between said jaws and twisted at right angles beyond but near said eye, a shank portion formed by said twist between said eye and said twisted portion, a rivet transversely through said jaws and said eye frictionally to clamp said eye between said jaws, said converging tongue portions of said jaws coacting with the shank portion of said clip arm when the clip is in use, thereby frictionally holding said clip arm in position.

4. An earring clip comprising a face plate, a bracket rigidly affixed to the back thereof and having a pair of jaws, each of said jaws having an asymmetrical tongue portion extending vertically outward therefrom, said tongue portions being aligned and converging toward each other at the ends thereof, said tongue portions occupying a small section of the periphery of said jaws and being spaced from the rear of said face plate, thereby to allow easy insertion of the lobe of an ear between said face plate and said tongues, a metal clip arm having an eye unitary therewith at right angles to the general plane thereof and interposed between said jaws, a rivet transversely through said jaws and said interposed eye to clamp said eye in place between said jaws, said clip arm having a shank portion between and frictionally engaged by said tongue when the clip is in use.

5. As an article of manufacture, a jewelry clip comprising a U-shaped bracket having a pair of jaws extending therefrom, each of said jaws having an asymmetrical tongue portion unitary therewith extending vertically outward therefrom at right angles to the length of said bracket, said tongue portions being aligned and converging toward each other at the ends thereof, a clip arm having an eye unitary therewith hinged at one end between said jaws and a shank portion near said eye, a rivet transversely through said jaws and said eye frictionally to clamp said eye between said jaws, said converging tongue portions of said jaws coacting with the shank portion of said clip arm when the clip is in use, thereby frictionally holding said clip arm in position.
